Application September 12, 1946, Serial No. 696,549

17 Claims. (Cl. 200—77)

1

The present invention relates to circuit closers, and more particularly to a novel slide contactor switch.

In switches of the slide contactor type heretofore designed, one of which, Patent No. 2,246,373, is a purely illustrative example, the contact areas are approximately of pin-point magnitude so that fractional deviations of cooperating parts from the ideal, due to faulty manufacture, careless assembly, or wear, result in poor electrical connections, arcing at the contacts, and loss of energy. It is also noteworthy that large production switches of the prior art have been so deficient in contacting area that it required large switch components to carry very small currents, with a consequent high cost and appreciable size of the switches. Obviously, this militated against the availability of the switches for many of the most common applications for switches. As a corollary it required very large and heavy switches to carry larger currents, with further undue increases in sizes and costs.

Some of the objects of the present invention are: to provide an improved snap switch for closing the terminals of an electric circuit; to provide a switch wherein contact areas are relatively large; to provide a switch so constructed and arranged as to materially reduce the danger of arcing and burning away of the contacts; to provide a switch which automatically maintains such a pressure on the contacts as will ensure maximum and efficient results; to provide a switch wherein a spring serves not only to bias the contactor to good electrical contact but also coacts with the manual or other shifting of the slide contactor to urge the contactor from one position to another with a pronounced high velocity snap action; to provide a slide switch in which with mere variations in sizes of parts, currents of practically any given magnitude can be controlled; to provide a slide switch of such simple construction and of such few parts that automatic assembly is facilitated; to provide a slide switch of extreme economy of manufacturing costs; to provide a snap switch utilizing a roller for bridging stationary contacts which automatically is caused to rotate during use to both effect self-wiping and new contact surfaces to the fixed contacts; to provide a slide switch of extremely low contact resistance; to provide a slide switch in which heat incident to arcing is quickly dissipated to open air due both to the large area of the contact terminals as well as to the short lengths of such terminals extending into the enclosure of the switch; to provide a slide switch

2

peculiarly well adapted to high current D. C. operation with adequate quenching of the spark; to provide a slide switch in which the increase of current carrying capacity is practically a linear function of increase of size of the parts; to provide a slide switch of extremely sharp and quick make and break and in which the speed of the make and break is substantially independent of the speed of operation of the slide member; to provide a slide switch utilizing a roller contact for bridging fixed contacts in which the speed of the break is a function of the weight of the roller; to provide a slide switch of high current-carrying capacity in a physically small switch; to provide a slide switch which is self-indexing and without an override; and to provide other objects and advantages as will become more apparent as the description proceeds.

In the accompanying drawings forming part of this description:

Fig. 1 represents a sectional elevation of a single pole, double throw snap switch embodying one form of the present invention.

Fig. 2 represents a transverse section therethrough taken on line 2—2 thereof.

Fig. 3 represents a fragmentary schematic illustration of the successive positions and deformations of the actuating spring device of the invention, showing at the top figure the roller contact seated firmly on two spaced contacts, with the spring substantially symmetrically disposed on the axle of the roller to push same down evenly against the contacts, the figure in the middle position indicates the change of deformation of the spring as pressure is applied endwise of the wire to bend same to change the resultant pressure on the axle of the roller just prior to its attainment of a resultant pressure line causing the roller to snap from the said two contacts and into circuit-making contact with another pair of contacts and the lower figure represents the final disposition of the roller and the new substantially symmetrical disposition of the spring exerting downward pressure from the spring upon the axle of the roller to cause even pressure thereof against the said two successive electrode contacts, in a three electrode switch having a single pole and a double throw.

Fig. 4 represents a fragmentary enlarged schematic fragment of the spring and roller showing the substantially symmetrical spring disposition according to the upper and lower figures of Fig. 3.

Fig. 5 represents a fragmentary enlarged schematic fragment of the spring and roller, showing the asymmetrical disposition of the spring and

the roller as the resultant pressure on the roller progresses from that which is preponderantly vertical toward a resultant line of pressure approaching the preponderantly horizontal.

Fig. 6 represents a sectional elevation of a double pole, double throw switch according to a modified form of the invention of Fig. 1.

Fig. 7 represents a section taken on line 1—1 of Fig. 6.

Fig. 8 represents a transverse section therethrough taken on line 8—8 of Fig. 7.

Fig. 9 represents a bottom or reflected plan of the slide element of the switch of Fig. 6.

Referring to Figs. 1 and 2 of the drawings, in an illustratively simplified form of the invention, an electrode plate 10 of insulating material, such as of "Bakelite" or the like, is provided, in which a series, in this case illustratively, three electrodes or contacts 11, 12, and 13 are mounted, as by staking, in evenly spaced relation in the plate. The contacts are extended a slight distance above the upper surface of the plate 10 in transversely elongated contacts respectively 14, 15, and 16, which are quite heavy and solid, and extend transversely of the plate for appreciable distances while providing clearance for the skirt of the slide element to be described. The contacts 14, 15, and 16 are in parallel relation and arranged for selective engagement by a circuit controlling roller to be described. The contacts are continued downwardly below the plate in the wiring terminals as indicated, for the attachment of such leads as may be desired. If the switch is to be a double throw, single pole switch, then the central electrode 12 will carry one side of the line current, and the outside electrodes 11 and 13 respectively will connect with the alternately energized circuits leading back to the other side of the line. If it is desired to provide a single throw switch between "on" and "off," the central electrode 12 will be energized as will one or the other of the electrodes 11 or 13, with the remaining electrode blank or out of a line circuit to form with the roller to be described an "off" setting. It is of importance that the great mass or body of the several electrodes are below the plate 10, and thus are outside of the switch housing to be described. The mounting of the electrodes in the stamped or otherwise formed plates 10 as an automatic machine operation will be appreciated.

A roller contact 17 is provided, having an outer peripheral contact-making area 18, of such total axial extent as to be substantially coextensive with the linear extent of the contacts 14, 15, and 16. In the center the roller is turned down or otherwise provided with a thin peripheral groove 20, leading to a transverse integral connecting axle 21. The roller diameter is such that when engaged between a pair of adjacent electrodes, illustratively 14 and 15, it is out of contact with the plate 10, and yet has such axial extent as to establish lines of contact with the respective electrodes with the only interruption being at the peripheral groove. The roller is mounted to seat and self-index and self-seat itself upon alternate pairs of electrodes, either 14 and 15, or 15 and 16, and at rest is pushed substantially normally of the plate into the circuit-making engagement noted. The push is by a spring of simplified nature having a central generally arcuate portion 22, arranged to be mounted in the groove 20 and to contact the periphery of the axle portion 21. It is an important function of the central curved portion of the spring to effect a resilient urge on the axle and thus upon the roller, either in a

generally symmetrical disposition in a direction normal to the plate 10, or in a generally asymmetrical disposition in a direction oblique to the normal, approaching the parallel to the plate 10. This spring function is accomplished, illustratively, by providing a pair of wings 23 and 24, formed as integral prolongations of the central curved portion 22, sweeping upwardly out of the horizontal by curved corners respectively 25 and 26. In the preferred form shown in Figs. 1 and 2, the spring wings terminate in ends lying in the axial extent of the wings as shown at 27 and 28 respectively.

In order to guide and slide the spring and thus the roller relative to the stationary plate 10 and the contacts which the latter carries, it is preferred to provide a unitary insulating block 30 such, for instance, as of a molded plastic, having a lower substantially planar face 31 defining the lower edge of a depending skirt 32, surrounding a central generally substantially arcuate recess 29 to house the roller 17 and provided with grooves 33 and 34, to receive the respective wings 23 and 24, with clearance between the respective ends 27 and 28 of the latter and the inner end surfaces 35 and 36 of the skirt 32. The block terminates in an actuating knob extension 37 of generally rectangular cross section.

A housing or casing is provided, preferably formed of metal, and comprising initially an upper plate 38 having depending side walls respectively 40 and 41, terminating in ears 42. For high voltage D. C. operation, it is preferred that the casing be formed of powdered sintered Alnico powder, which is highly magnetized. The upper plate of the housing has an aperture 43 in which the rectangular knob 37 of the sliding element is disposed, when the upper surface of the block 30 is in slidably guided relation to the inner surface of the plate. The lateral surfaces of the block 30 are slidably guided by the respective side walls of the casing or housing formed of the open ended compartment defined by the top plate and the side walls.

It will be observed that the parts as so far described are predeterminedly shaped and organized so as to conduce toward automatic assembly. Thus, the pre-shaped housing is mounted with the open end extending vertically upward, the knob 37 is threaded downwardly through the opening 43, and the block is mounted in the case, the spring element is dropped into the grooves with the central curved portion disposed in the curved recess 32, the roller contact is dropped into the recess straddling the spring portion 22 so that the axle element of the roller contacts and physically engages the arcuate portion 22 of the spring, the pre-formed plate 10 with the mounted electrodes or contacts, and side notches 39 is dropped or forced into the space between the lugs or ears 42, with the lugs received in notches 39 and with the plate 10 seating against the lower edges of the side walls 40 and 41 of the housing. This seating action thus forces the fixed contacts to bear against the roller and to move it against the resilience of the spring to cause the roller to react against the electrode contacts, while resiliently supporting the slide element in substantially frictionless slightly spaced relation of the lower planar surface relative to the upper surface of the plate 10. As a completion of the automatic assembly, the lugs or ears 42 are peened over against the lower surface of the plate 10, and the assembly is complete.

The operation of the switch is as follows: As-

suming that the roller is disposed as shown at the top in Fig. 3, at the right, in physical and electrical engagement with the electrode contacts, the spring slides in the slide block 30 to dispose itself substantially symmetrically of the axle as indicated in that figure, although it need not at this instant be exactly symmetrical of the block 30. At this point the ends 27 and 28 of the spring wings or arms 23 and 24 are respectively more or less spaced from the abutting inner surfaces 35 and 36 of the slide member and the spring pressure line is substantially perpendicular to the plate bisecting the contacts 15 and 16 bridged by the roller and the knob has been disposed in the slot 43 in substantial engagement with or at least adjacent to the right hand end of the slot. Assuming that this controls a given circuit through electrode contacts 15 and 16 and it is desired to reverse the switch so as to open the said circuit and to close a circuit through electrode contacts 15 and 14, the operator slides the slide member longitudinally of the housing parallel to the plate 10 toward the left in Fig. 3. In the course of this shift, the inner abutting surface 36 of the slide member abuts the free end 28 of the spring to which it is juxtaposed and starts to apply force substantially endwise thereof. As the line of applied force is horizontal, or substantially parallel to the plate 10, and as the wing 24 of the spring is angularly divergent from this line of force or pressure, the curved central portion 22 of the spring is urged toward the left, progressively shifting the point of contact of the curve 22 on the axle 21 angularly of the axle from its initial rest point on a diameter of the axle substantially bisecting the contacts 15 and 16 bridged by the roller to points on the axle on diameters angularly divergent from the said initial diameter. Up to a final point of contact, owing to the seating of the roller between the contact electrodes 16 and 15 the roller resists shifting motion. The continuation of the endwise pressure on the wing 24 of the spring forces the spring to a position of asymmetry in which the curved connection 26 between the wing 24 and the curved central portion 22 moves downwardly toward the plate 10, while the other connection, the curved portion 25 between the central curved portion 22 and the other wing 23 of the spring, moves upwardly so that a plane tangent to the curves 25 and 26 is and becomes increasingly angularly more divergent from the plane of the plate 10. This action causes the curved central portion 22 of the spring with deformation to move its point of engagement with the axle still closer to the plate 10 on a diameter of the axle and roller which is progressively more acutely angularly divergent from the plate 10 with an angularly shifting resultant pressure along that line. This progressively shifting resultant is composed of a diminishing vertical pressure on the roller and an increasing and ultimately a preponderating pressure longitudinally of the casing, parallel to the plate 10. At some point in the developing shift of pressures the preponderance of pressure longitudinally of the plate forces the axle and thus the roller longitudinally of the plate, causing the roller to break its engagement with the contact electrode 16, and to snap very quickly cross the central electrode contact, during which it must either wipe on or turn somewhat about the central electrode 15. However, at this juncture the central portion 22 of the spring is so cocked that there is an effective

clearance between the axle and the spring portion 22 in the line of motion of the axle of the roller in moving from the crest of contact 15 at which it is out of engagement with both contacts 14 and 16 in moving to seated position of the roller on both contacts 15 and 14, which momentarily permits relatively catapulted "free flight" of the roller during which it can change its relative angular position, before again becoming engaged tightly between the curve 22 of the spring and the two electrodes 14 and 15. This is an important feature as it enables the roller to progress angularly as it switches back and forth to present new contact areas to the fixed electrode contacts. It also enables both a quick "make" as well as "break." Moreover, and of importance, is the fact that the spring portion 22 is intersected by the axle at the end of the free flight of the roller, to absorb some of the kinetic energy of the roller to damp same and force it downward into seated indexed symmetrical balanced position on the contacts 14 and 15 without either bouncing or overriding. The arcuate recess 29 is also of such vertical and longitudinal dimensions as to permit this jump or propelled movement, while being laterally of such relatively close configuration as to exert slightly spaced areas having guiding functions on the roller without binding same.

30 It will be apparent that the switch as thus described is cheap, made of few and simplified parts, and that in the enclosure formed by the sliding block or member 30 and the plate 10, the amount of metal of the switch is a minimum as the roller is thus substantially completely housed, while the contacts only expose the mere terminal edge portions extending from the floor of the plate 10. It will be understood that when the powdered sintered Alnico case is used the magnetic flux of the highly magnetized case at its most intense path between the poles formed of the terminals of the side walls, which is substantially across the fixed contacts, quickly quenches the arc formed thereat with D. C. current.

45 It will be evident that many modifications can be made in the principle incorporated in the switch just described without departing from the spirit of the invention. Thus, it will be clear that if desired gangs of switches can be made by providing a plurality of the housings as integral prolongations, in each of which the switch assembly as described is installed so as to effect a plurality of separately actuatable switches in a single entity. It will also be obvious that although in the preferred form the alignment of the electrodes is in a plane, they can equally well be disposed in an arc, so that the roller axis moves in an arc, except for the deviations therefrom incident to switching, as noted, instead of in the substantial plane as described above. Further, it may be desired to cause a plurality of switches to be disposed in interlocking arrangements, such that a movement of one switch in moving toward one circuit controlling disposition is accompanied by a complementary synchronous movement of another switch toward unswitching or other changes of circuits.

70 Furthermore, the principles involved can be used to excellent advantage in plural circuit controls, as indicated in Figs. 6 to 9 inclusive. Thus, referring to these figures, the plate 45 is provided with one set of electrode contacts respectively 46, 47, and 48 extending in spaced series along one side of the plate 45, and in spaced relation

but in lateral alignment with the respective electrodes, a second set of electrodes will be disposed, as indicated in Fig. 7 at 50, 51, and 52. The roller 53 as indicated in Fig. 8 comprises one metallic, or metallic surface roller 54, mounted on an insulating axle 55, and having an inner insulating facing washer or the like 56 forming one surface of a peripheral groove 57, and a metal roller or metallic faced roller 58 also mounted on the axle and provided on its inner face with the insulating washer 60 forming the other face of the groove 57. The spring as previously described may be used to embrace and control the roller as in the earlier figures, although if desired a further modification may be made as shown in Fig. 6. In this case, the sliding insulating member for the switch 61 is provided with the lower peripheral skirt 62, surrounding the central arcuate recess 63, and leading by the grooves respectively 64 and 65 to the recesses or apertures 66 and 67 formed in the block. These latter are preferably of such longitudinal extent as to have clearance in both directions from the bent terminal ends of the spring to be described, although excellent results attach to having the recesses just large enough to receive said ends of the springs. The spring for actuating the roller has the similar central curved portion 68 merging by the curves 70 and 71 into the oppositely extending upwardly inclined wings 72 and 73 having the angularly divergent ends respectively 74 and 75, which seat loosely or tightly in the recesses 66 and 67. The block has the control or actuating knob 76. The housing 77 is similar to that already described, having the recess 78. The roller functions as before except that the roller component parts forming the circuit controlling members are relatively insulated from each other and from the spring, and the switch in its actuation simultaneously controls circuits between electrodes 51 and 52 on one half, and 47 and 48 on the other, and in alternation thereto, simultaneously controls circuits between contacts 51 and 50 on one side and 47 and 46 on the other. The possibility of additional sets of rollers and contacts for additional circuits will be understood, and the compactness of such single switch for the control of pluralities of sets of electrodes will also be understood.

The advantages, simplicity, and extremely low cost of the switch will be apparent.

Having thus described my invention, I claim:

1. A slide switch comprising a housing, a slide member in the housing and having a restricted travel longitudinally of the housing, said slide member having a lower recess, said slide member also having a spring element receiving groove, a plurality of contacts disposed transversely in the housing in mutually spaced relation longitudinally of the housing, a substantially symmetrical spring element mounted in the groove and having a curved portion extending into the recess, a roller element comprising two roller surfaces connected by an axial portion of reduced diameter compared to the roller surfaces and arranged for movement in the recess, said roller element arranged to bridge selected pairs of contacts and to establish lines of contact therewith in response to pressure from the curved portion of the spring element engaging the axial portion of the roller, means for transmitting thrust to the spring element longitudinally of the housing to develop longitudinal pressure on the roller to cause it to snap from one bridging re-

lation with one pair of contacts to bridging relation to another pair of contacts in response to longitudinal sliding movement of the slide member.

5. 2. A slide switch comprising a roller having a pair of spaced roller elements connected by an axle, a spring element including a substantially central portion formed in a substantial arc, means mounting the spring element so that the substantial arc thereof is disposed between the roller elements in contact with the said axle, contacts bridged by the roller elements, said means for mounting the spring element arranged to shift it in a path transverse of the roller and of the contacts, said spring element arranged during the shift to change its point of bearing on the axle from a normal position urging the roller elements in a direction generally bisecting the contacts with which the roller is in contact to a point of bearing generally transverse of the contacts to snap the roller from its position bridging a pair of contacts.

3. A switch comprising a support, two contacts on the support in spaced relation extending above the surface of the support, said contacts being in substantially parallel spaced relation, a roller having a cylindrical contour and arranged to seat upon the parallel contacts with a portion of its periphery below the level of the said contacts, said roller having a peripheral groove, a spring engaging the roller in the groove, said spring having a portion curved to enter the groove and having reentrantly bent wings the ends of which are in a plane above the juncture of said wings with the curved portion, and means imposing endwise pressure on a wing to deform the curved portion of the spring to exert a resultant thrust on the roller having a component preponderantly transverse to the axis of the roller and of the two contacts to force the roller from the engagement with the said contacts.

4. A switch comprising an insulating support, a plurality of spaced contacts mounted upon and extending above the said support in parallel spaced relation, a roller contact having a peripheral groove defining an axle and arranged to seat upon said spaced contacts with an arcuate portion of the roller extending downwardly below the fixed contacts out of contact with the said insulating base, a spring having a central portion disposed in the groove, engaging the axle and merging into integral extensions, means for exerting compressing pressure on one of said extensions to deform the central portion to change an initial downward pressure on the axle into a pressure transverse of the axle and of the contacts to move the roller as a function of deformation of said spring.

5. A slide switch comprising an insulating support, a pair of contacts mounted on and extending above said support in spaced relation, a second pair of contacts mounted on the support in spaced relation, the contacts of one pair being in aligned spaced relation to the contacts of the other pair, a roller comprising a pair of spaced metallic members of cylindrical contour and a connecting axle, means for moving the roller relative to both of said pairs of contacts, means insulating the metallic contact elements from each other and from said means, said means for moving the roller comprising a spring having angularly divergent wings and a central generally curved portion, and means for exerting deforming pressure on the spring to cause it to exert a progressively shifting pressure on the

axle to move the roller from the said pairs of contacts.

6. A switch comprising control means having a path of movement, means guiding the means in the path of movement, an insulating support, a pair of contacts mounted in and extending above the support, a roller contact, means exerting pressure on the roller to force the roller against the contacts and deformable under pressure from the control means to force the roller out of engagement with both of said contacts as the means moves on its path of movement, said pressure exerting means comprising a spring having a central generally arcuate portion and divergent wings leading into the arcuate portion by corners both respectively substantially tangent to a common plane which is substantially parallel to the plane of the contacts in the undeformed spring condition and which common plane is angularly inclined from the plane of the contacts in the deformed spring condition.

7. A switch comprising a movable control element, a guide housing in which the element has guided movement, contact elements in the guide housing juxtaposed to the control element, said control element having a recess in the side toward the contact elements, a roller contact having a bearing portion, resilient means in said recess having a generally arcuate portion and disposed with said arcuate portion engaging the said bearing portion on one side of the resilient means and exerting resilient pressure thereon when at rest, and said resilient means disposed in engagement on the other side thereof by the control element, said resilient means being disposed for limited bodily shifting movements relative to the control element transverse of the contacts and being movable with said control element for changing the direction of resilient pressure on the bearing element arising from engagement of said generally arcuate portion with said bearing portion to shift the roller contact relative to said contact elements.

8. A switch comprising a guide housing including an insulating strip, a plurality of contacts mounted on the insulating strip and disposed in a series longitudinally of the guide housing, a roller contact having a bearing portion and arranged to bridge adjacent contacts, a movable control element mounted on the guide housing for movement longitudinal of the series of contacts, a spring biased device comprising a generally centrally disposed substantially arcuate portion between wings, said control element being contoured to house and permit limited bodily motion of the generally arcuate portion generally axially of the wings longitudinally of the control element, said spring biased device arranged to be resiliently engaged between the control element and the bearing portion of said roller with the generally arcuate portion of the spring biased device engaging said bearing portion to bias the roller toward engaging both of a pair of spaced contacts, and said spring biased device arranged to move with the control element to impart movement to the roller longitudinal of the housing to move said roller out of bridging contact with said pair of adjacent contacts through pressure from said substantially arcuate portion upon said bearing portion.

9. A switch comprising a plurality of aligned relatively insulated contacts having appreciable length transverse of the alignment, a roller of appreciable axial extent arranged to selectively bridge pairs of adjacent contacts, a bearing ele-

ment on said roller, a movable control element, means guiding the control element for movement parallel to the general line of said contacts and for limiting the motion of the control element away from said contacts, an elongated spring element having a median substantially arcuate portion arranged for abutting engagement with the bearing guide of said roller contact and for sliding engagement with the control element to force the latter toward the means guiding the control element and the roller toward a pair of adjacent contacts to which it is juxtaposed, and means on the control element limiting the sliding of the spring element to cause the spring element to move with the control element longitudinally of the aligned contacts to force the roller out of bridging relation to said selected pair of contacts to which it is juxtaposed.

10. A switch comprising guide means, a control element mounted for guided movement relative to the guide means, a plurality of spaced contacts mounted on the guide means, a roller contact having a bearing portion and arranged to bridge adjacent contacts, spring means comprising a central substantially curved portion and wings extending in opposite directions from the curved portion, said substantially curved portion being of larger radius than said bearing portion and having an opening between the wings, said substantially curved portion disposed substantially in a plane normal to the axis of said roller and engaged between the control element and the bearing portion of said roller, and means on said control element engaging a wing on said substantially curved portion for forcing said substantially curved portion to move with said control element to move said roller.

11. A switch comprising guide means, a control element mounted for guided movement relative to said guide means in a fixed path and having abutment elements spaced longitudinally of said path, a plurality of contacts on said guide means spaced longitudinally of said path, a roller contact arranged to bridge a pair of said contacts and having a bearing portion, a spring disposed generally longitudinally of said path and of predeterminedly shorter length than the distance between said abutments so as to have limited bodily shifting motion between said abutments and relative to said control element, said spring including a substantially median curved portion larger than and disposed for resilient engagement with the bearing portion of said roller contact and arranged to develop a lateral component against said bearing portion of said roller when shifted through pressure from an abutment when moving with the control element to move the roller on said path out of its said bridging relation.

12. A switch comprising guide means, a plurality of aligned relatively spaced contacts mounted on the guide means, a control element movable relative to the guide means and to the respective contacts, a roller contact having a bearing portion and disposed to selectively bridge pairs of adjacent contacts of said plurality, spring means comprising wings and an intermediate curved portion engaging said bearing portion of said roller and of such curvature as to be substantially tangential to said bearing portion with contacting areas of the spring and bearing portion of the roller disposed in a given angular relation to the axis of the roller with the parts at rest and with the roller bridging one of said pairs of contacts, said wings slidably en-

gaging said control element, means on said control element for limiting the bodily sliding movement of said spring means relative to said control element, said spring means disposed for movement with said control element and to change the angular relationship of the contacting areas of the spring means and bearing portion to the axis of the roller to force the roller transversely out of bridging relation to one said pair of contacts into bridging relationship to the other of said pairs, and said spring means arranged in response to movement of the roller in moving from bridging one pair of contacts to the next said pair thereof to move bodily relative to the control element to cause the substantial resumption of the first mentioned angular relationship of the contacting areas of the curved spring portion and the bearing portion of the roller to the axis of said roller.

13. A switch comprising guide means, a control element mounted for guided movement relative to the guide means, a roller contact comprising two roller portions connected by an axle and defining a peripheral groove, contact means on the guide means disposed for bridging by said roller portions, spring means having a generally curved portion larger than the axle disposed in part at least in said groove engaging the axle substantially tangentially thereof, said generally curved portion of said spring means lying and maintained substantially in a plane parallel to the guided movement of said control element and normal to said axle, said generally curved portion of the spring means disposed for bodily shifting with and also relative to said control means and arranged at rest to exert a bias on the roller toward said contact means and when moving with the control means to exert a bias on said roller transverse of said contacts.

14. A switch comprising supporting means, a plurality of metallic members disposed on the means in substantially aligned mutually spaced relation and of which at least two are contacts, annular bridging means having a bearing portion and arranged selectively to bridge one or another pair of adjacent members, a movable control element juxtaposed to and movable generally parallel to the line of members, spring means comprising a generally C-shaped element larger than and bearing tangentially against the bearing portion of the bridging means and arranged at rest to exert a bias against said bearing portion to bias the annular means against the instantaneously bridged members with the open end of the C-shaped element substantially symmetrically disposed about a diameter of the bridging element bisecting said instantaneously bridged members, and means responsive to thrust from the control element in its line of movement for distorting the C-shaped element so as to shift the tangential engagement thereof with the bearing portion angularly of the latter to effect clearance between the element and said bearing portion in said line of movement while moving the said open end thereof to asymmetry to said diameter so as to transmit a thrust to said annular bridging means in said line to move same from the instantaneously bridging relation into bridging relation to another pair of members with momentary free flight relative to the spring means.

15. A self-indexing switch comprised of a first portion and a second portion of which one is relatively movable and one is relatively fixed,

complemental means on the respective portions for guiding one portion relative to the other in a guided path of relative movement, a plurality of linearly extending bars mounted on the first portion in parallel spaced relation in alignment on said path and forming a first and second pair of adjacent bars of which one bar is common to both pairs, a cylindrical contactor including an axle of smaller diameter than the contactor and mounted for controlled movement relative to both portions in a plane aligned with said path normal to the respective bars, the axis of said contactor being parallel to said bars, the diameter of said contactor being greater than said spaced relation to provide two peripherally spaced substantial lines of contact when the contactor is disposed in tangential bridging relation to a first pair of bars, spring biased shifting means between the second portion and said axle and comprising a device for enclosing the axle on three sides thereof, said device having internal clearances in the line of said path greater than the diameter of said axle, and means for producing relative thrust from said device against said axle in response to relative motion of the portions to force the contactor out of bridging relation with said first pair of bars and into bridging relation with the second pair of bars, said contactor being biased into self-indexed relation with said second pair of bars as the axle adjusts itself in the clearance in said device.

16. A self-indexing switch comprising a cylindrical roller contactor including an axle of smaller diameter than the cylindrical contactor, a support, a plurality of bars mounted on the support in parallel spaced relation parallel to the axis of the contactor, said spaced relation being less than the diameter of said contactor to provide line contacts respectively at opposite sides of said contactor when the contactor is mounted on a pair of adjacent bars bridging same in tangential relation to the bars, a movable housing having a recess to receive said contactor, said recess being longer than the diameter of said contactor to provide side clearances for controlled movement of said contactor, guide means on the support for guiding the movable housing for movement in a path generally transverse of said bars, and contactor shifting means comprising an open jaw straddling said axle with a lost motion connection in the line of said path whereby relative movement of said axle and jaw is provided, said shifting means further comprising biasing means reacting between the housing and said axle to urge the contactor into bridging relation with a selected pair of bars, whereby the contactor rising and then falling about the far bar of the pair in the path of movement of the housing moves relative to both the housing and said jaw and is self-indexed.

17. A self-indexing switch comprising a cylindrical roller contactor including an axle of smaller diameter than the cylindrical contactor, a support, a plurality of bars mounted on the support in parallel spaced relation parallel to the axis of the contactor, said spaced relation being less than the diameter of said contactor to provide line contacts respectively at opposite sides of said contactor when the contactor is mounted on a pair of adjacent bars bridging same in tangential relation to the bars, a movable housing having a recess to receive said contactor, said recess being longer than the diameter of said contactor to provide side clearances for con-

13

trolled movement of said contactor, guide means on the support for guiding the movable housing for movement in a path generally transverse of said bars, contactor shifting means comprising an open jaw straddling said axle with a lost motion connection in the line of said path whereby relative movement of said axle and jaw is provided, said shifting means further comprising biasing means reacting between the housing and said axle to urge the contactor into bridging relation with a selected pair of bars, and means incorporating a limited lost motion in the housing to develop thrust in the general line of said path to force the contactor out of said bridging relation with said pair of bars, whereby the contactor rising and then falling about the far bar of the pair in the path of movement of the housing moves relative to both the housing and said jaw and is self-indexed, and the jaw adjusts itself in the limited lost motion in the housing. 20
